CLAIM

The ornamental design for a packing box for water hose, as shown and described.

DESCRIPTION

FIG. 1 is a front, right and top perspective view of a packing box for water hose showing my new design;

FIG. 2 is a front elevational view thereof;

FIG. 3 is a rear elevational view thereof;

FIG. 4 is a left elevational view thereof;

FIG. 5 is a right elevational view thereof;

FIG. 6 is a top view thereof;

FIG. 7 is a bottom view thereof; and,

FIG. 8 is a rear, right and bottom perspective view of a packing box for water hose in an alternate configuration of use.

The broken line portion of the drawings is included to show unclaimed subject matter only and forms no part of the claimed design.
